LOOM DOBBY

Clarence R. Kronoff, Worcester, Mass., assignor
to Crompton & Knowles Loom Works, Worcester,
Mass., a corporation of Massachusetts

Application September 7, 1940, Serial No. 355,841

7 Claims. (Cl. 139—71)

This invention relates to improvements in loom dobbies and it is the general object of the invention to provide a dobbey employing many of the currently used parts of such a mechanism but wherein the lifting jack for the harnesses is so mounted as to provide a considerably increased warp shed opening.

Loom dobbey mechanisms customarily employ a pair of oppositely reciprocating lifter knives which cooperate with upper and lower sets of hooks controlled by the pattern mechanism. The hooks are connected in pairs with the upper and lower ends of vertical dobbey back levers which in turn are pivoted to the harness lifting jacks. Heretofore the dobbey jacks have moved around a pivot below the lower set of hooks and the dobbey back levers. In order to increase the angular motion of the jack I have raised its fulcrum and constructed the latter so that it will not interfere with the back levers.

The levers are swung outwardly from their normal position by the hooks attached to them and since either hook may be engaged by its knife the dobbey back lever can assume either of two diagonal positions which define a zone of operation of the levers. In order to achieve maximum lifting effect on the harnesses it is desirable to cause the jacks to move about a center which is under the mid point between the two extreme positions of the pivotal connection between the back lever and the jack. This point, however, lies within the aforesaid zone of operation of the back levers and it is an important object of my present invention to construct an arcuate pivotal support for the jacks the center of which either lies within or is close to the aforesaid range of operation. The support is so placed that no part of it lies within said zone.

It is a further object of my present invention to provide the pivoted support for the jacks with supporting ears or the like having provision for attachment with the dobbey frame at points lying substantially on the center of the arcuate bearing surface, the purpose of this construction being to maintain the guide surface for the jacks in a correct position with respect to other centers of the dobbey while permitting slight variations in the actual placing of the arcuate support, such as might arise under manufacturing conditions.

It is a further object of my invention to provide a transverse member for the dobbey which will serve the dual purpose of supporting the lower ends of the dobbey back levers and also constitute the pivotal support for the harness jacks.

It is another object of my invention to provide a support for the jacks which will permit their removal without disturbing the support, the latter remaining permanently connected to the dobbey and the jacks being so constructed that they can be removed one at a time while the others are held in place by the support.

With these and other objects in view which will appear as the description proceeds, my invention resides in the combination and arrangement of parts hereinafter described and set forth.

In the accompanying drawing, wherein two forms of my invention are shown—

15 Fig. 1 is a central vertical section through a dobbey made according to the preferred form of my present invention, showing the dobbey jack and its operating parts in two different positions,

20 Fig. 2 is an end elevation of the dobbey looking from the center of the loom in the direction of arrow 2, Fig. 1,

Fig. 3 is a perspective view of the arcuate pivotal support for the harness lifting jacks shown in Figs. 1 and 2,

25 Fig. 4 is an enlarged view similar to a portion of Fig. 3 showing the modified form of the invention,

Fig. 5 is an end view of the arcuate support shown in Fig. 4, and

Fig. 6 is a diagrammatic view showing the zone of operation of the dobbey back levers with respect to the center around which the harness lifting jacks swing.

35 Referring particularly to Figs. 1 and 2, the dobbey comprises a pair of spaced end plates 10 each provided with upper and lower horizontal slots 11 and 12, respectively. Top and bottom knives 13 and 14 oscillate in opposite directions 40 in their respective slots by mechanism not shown, each knife having an outward motion to the left on one beat of the loom while the other knife has an inward motion to the right, and the motions of the two knives being reversed on the next pick of the loom.

The knives cooperate with top and bottom hooks 15 and 16, respectively, the positions of which with respect to the knives is determined by pattern mechanism not shown. Each top hook is pivoted as at 17 to a dobbey back lever 18 the lower end of which is pivoted as at 19 to one of the bottom hooks 16. In this way each dobbey back lever is connected to a pair of hooks, one to be actuated by the top knife and the other by the bottom knife, according to the de-

mands of the pattern being woven. The dobby has a top cross girt 20 extending between and secured to the plates 10 to limit right hand motion of the tops of the levers 18. The dobby is provided with a number of the levers 18 each of which can be moved independently of the others on each pick of the loom.

At its mid point each lever 18 is pivoted as at 22 to a harness lifting jack J the upper end of which is provided with a series of notches 23 one of which will ordinarily receive a harness lifter cord 24. It is a characteristic feature of a dobby that the cord 24 will have exerted thereon a force directed to the right as indicated by arrow a in Fig. 1 by the weight of the harness frame not shown. This condition tends to move the top of the jack to the right or toward the center of the loom, and also holds the top of levers 18 against top girt 20.

Fig. 6 shows diagrammatically the zone of operations of the levers 18. This zone Z is bounded on the right by the normal position of lever 18 shown in full lines, Fig. 1, and at its top and bottom by the arcuate paths traversed by upper and lower ends, respectively, of the lever. The left boundary of the zone is determined by the two diagonal positions which the lever 18 can assume, one of which is shown in dotted lines, Fig. 1. The levers must be free to move within this zone and any structure extending into it would interfere with the operation of the dobby. The upper part U of the zone is due to movement of top hook 15, while the lower part L is due to movement of the lower hook.

The parts of the dobby thus far described are of common construction, the hooks, knives, and dobby back levers being operated in the usual manner and motion being imparted in the harness jacks through the pivotal connections 22.

In carrying my invention into effect I provide the lower end of each of the harness jacks J with an arcuate bearing surface 30 which rests against and slides along an arcuate pivotal support 31. Support 31 in the preferred form is provided at each end thereof with an ear 32, having a perforation 33 to receive a holding bolt 34 by which the support is held in fixed position with respect to the frames 10 between which it extends. In order to give the jack J maximum motion it should move about a center which is vertically below the mid point between the two extreme positions which can be assumed by the pivotal connection 22. In Fig. 1 this pivotal connection is shown in full lines in its right extreme position and in dotted lines in its left extreme position. The most favorable position for the axis of the jack would therefore be on a vertical line which passes through the zone Z. Heretofore the axis for the jacks has been located on the aforesaid vertical line but below the lower set of hooks 16, but in such a construction the ratio between the power and working arms of the harness jack has been relatively low, thereby setting an objectionable limit to the height of the warp shed.

In order to increase the ratio between the power and working arms of the jack I raise its center toward pivot 22 to some such point as designated by the x mark C in Figs. 1 and 6. It is apparent, however, that this center lies within the aforesaid zone of operation of levers 18 and it is for this reason that I form the support 31 as shown for instance in Figs. 1 and 3, with a parti-cylindrical surface 35 the axis of which extends transversely of the dobby and harness jacks and passes through the point C. The arcuate

bearing surfaces 30 of the jacks slide vertically along the cylindrical surface 35 and cause the jacks to move about center C without interfering in any way with movement of the hooks 16 and levers 18. The support 31 lies entirely outside the zone Z.

By the construction set forth in Fig. 1 the distance between the point C and the axis 22 is less with respect to the distance between said point C and the top notch 23 than formerly, with the result that the tops of the jacks can be given considerably more motion with resultant increase in the heights of the warp sheds.

In the preferred form of the invention the perforations 33 need not necessarily bear any definite relation with respect to the surface 35, but in the form of the invention shown in Figs. 4 and 5 I provide a modified support 40 having a parti-cylindrical surface 41 in all respects similar to surface 35. Lateral ears 42 on support 40 have perforations 43 the centers of which lie on the axis of the surface 41, as indicated by arrow r, Fig. 5. Each securing bolt 44 in the modified form therefore has its axis co-incident with the center of the surface 41 around which the jacks move and any slight mis-adjustment of the support 40 will not alter the center of the jacks.

It has heretofore been customary to provide the lower part of the dobby with a girt similar to that shown at 20 for the top of the dobby. A further feature of my present invention is to provide the pivotal support 31 with a surface 37 along which the bottom right edge of levers 18 may slide when the top hook is moved outwardly or to the left by the upper knife. The modified support 40 may be provided with a guide surface 45 similar in function to the surface 37 of the preferred form of the support. In this way I combine a guide for the lower part of the levers 18 with an arcuate support for the harness jacks, causing supports 31 and 40 each to perform two functions heretofore accomplished by two separate parts.

In order to prevent the jacks from becoming displaced during assembly, and to permit their removal one by one, I provide a guide pin 38 extending between the plates 10 for engagement with an arcuate surface 39 on the inner edge of the jack, this surface being concentric with the axis C.

Prior to placing the jacks in the dobby the top and bottom cross girts 30 and 31, and also the rod 38 will be placed in position. The jacks will then be moved to the extreme left hand position indicated by the short dotted line b in Fig. 1 against the right hand side of the top girt 20 with the arcuate bearing close to the bottom support 31. In this position the bottom of a narrow foot 50 at the lower end of the jack lying between the concentric surfaces 30 and 39 will be able to slide down between rod 38 and surface 30 to permit a right hand angular motion of the jack with the surface 30 sliding on the surface 35 around axis C as a center. Under the conditions of assembly the jacks will not be connected to the harness cords 24 nor will their right hand positions be determined by the levers 18, since the latter are not connected to the jacks until after assembly. It is for this reason that I provide the heel 60 on the jack which extends over the rod 38 to serve as a support to hold the jacks in place in a position approximating that shown in full lines in Fig. 1. After all the jacks are inserted into the dobby, they are moved to the left one by one and the levers 18 connected to them, after which the

jacks will again move to the right by their weight but will now be limited in their motion by engagement of the top and bottom of lever 18 with the corresponding cross girts and the heel 60 will be slightly above the rod 38. If it should be necessary to remove one of the jacks it will be swung to the extreme left hand position, the lever 18 disconnected, and then raised while rod 38 is still in position to support the other jacks. It will be noted from Fig. 1 that the rod 38 is located close to the bottom of foot 50 when the jack is in its left hand position and it is because of this location of pin 38 that the jack can be removed.

Foot 50 is long enough to provide adequate bearing contact with surface 30 when the jack is in the dotted line position shown in Fig. 1. I have found that the proper length of wearing surface can be obtained if the parts are so proportioned that a line drawn between the bottom 51 of surface 30 and the axis 22 lies to the left, or on the lever side of the upper end 52 of the bearing surface 30. When the parts are in the full line position shown in Fig. 1, point 52 should be as near as convenient to the lever 18 to insure maximum bearing surface between the jack and the surface 35, but when lever 18 is moved to the dotted line position it will move a considerable distance away from point 52. I find however that when the top hook 15 is moved to the left to move the lever through the range of movements indicated at U in Fig. 6, no objectionable engagement will occur between the lever and the point 52 of the jack bearing even though part of the jack moves into the aforesaid zone of operation, provided there is a slight clearance at the start of motion of the lever. This clearance can be provided by having point 52 located to the right of a line joining point 51 and axis 22. Interference is avoided also due to the fact that the lower end of lever 18 is not far removed from the center C and turns at approximately the same rate as does the jack. This last named relation permits the use of relatively long bearing surfaces on the jack and bottom girt and grows out of the fact that the lower end of the lever is in substantial alignment with the arcuate bearing surface on the jack. Ample bearing surface is provided despite the fact that the arcuate contact is considerably less than 180°.

In operation, the reciprocating knives will pick up one or the other of the hooks and the lever 18 will be moved from its normally vertical position to a diagonal position. If the bottom hook is pulled outwardly or to the left the center 22 will move from its right extreme position to the left extreme position and cause the guide surface 30 of the jack to slide upwardly in a curved path over the arcuate surface 35 and cause movement of the top of the jack around the center C. At the same time the top of lever 18 will slide downwardly a short distance along the cross girt 20. Should the upper hook be pulled outwardly the top of lever 18 will move to the left and center 22 will again assume its left extreme position and cause rocking of the jack as already described, but in this instance the lower end of lever 18 will slide upwardly along the surface 37 of the arcuate support. Upon return motion of the lever 18 to its normal position, regardless of which hook had previously moved to the left, the surface 30 of the jack will slide downwardly in a curved path along the arcuate surface 35. A similar operation will occur when the modified form of arcuate support as shown in Figs. 4 and 5 is used.

From the foregoing it will be seen that I have

provided a simple means for giving increased motion to the harness lifting jack of a dobby the greater part of which is constructed of levers and hooks of common construction. It will further be seen that the jack moves around an imaginary center which lies within the zone of operation of the levers 18, hence the latter are free to move without interference on the part of the supports 31 or 40. In the modified form of the invention the securing bolts 44 are co-axial with the cylindrical surface 41 so that slight misplacements of the support 40 will not alter the location of the center about which the jacks J oscillate. It will also be seen that the arcuate guide for the jacks provides a support for the lower end of the levers 18. The fact that the upper end of the jacks are constantly acted upon by the forces acting in the direction of arrow a, Fig. 1, serves to hold the arcuate guide surfaces 30 against the surfaces 35 or 41, depending upon whether the preferred or modified form of arcuate support is employed, and the pin 38 serves to hold the jacks in position while they are being connected to their respective harness frames.

Furthermore, since the lower end of the lever 18 is normally close to the arcuate bearing surface of the corresponding jack, the sliding curved surfaces of both the jack and the cross girt can be made relatively long so that pressure between the jack and its support is comparatively low. As a more detailed advantage of the invention the jack is so constructed that a line joining the lowest point of the surface 30 with the axis of lever 18 passes to one side of point 52, the latter being on the same side of this line as is the curved bearing 30 and the body of the jack.

Having thus described my invention it will be seen that changes and modifications may be made therein by those skilled in the art without departing from the spirit and scope of the invention and I do not wish to be limited to the details herein disclosed, but what I claim is:

1. In a loom dobby having a pair of spaced side plate frames between which are located a series of levers each of which has a dobby hook pivoted to the top thereof and another dobby hook pivoted to the bottom thereof, the dobby having reciprocating knives supported by and movable with respect to the side frames to engage the hooks and move the latter together with the levers through a given zone of operation, a series of harness lifting jacks each of which is pivoted to one of the aforesaid levers, means on the lower end of each jack defining an arcuate bearing surface, a support for the jacks extending between the side frames and having an arcuate bearing surface to engage and have sliding relation with respect to the bearing surfaces of the harness jacks, said support being located outside the zone of operations of the levers and hooks and said bearing surfaces of the jacks and support being concentric with a center located within said zone of operations of the levers and hooks, and means to secure the support to the side frames along the center of said bearing surfaces of the jacks and the support, whereby slight variations in the location of the support will maintain the arcuate surface thereof concentric with the aforesaid center for all positions of the support around said securing means.

2. In a loom dobby having a pair of spaced side plates between which are located a series of levers each of which has a dobby hook pivoted to the top thereof and another dobby hook pivoted to the bottom thereof, the dobby having reciprocating

ing knives supported by and movable with respect to the side plates to engage the hooks and move the latter together with the levers through a given zone of operation, a series of harness lifting jacks each of which is pivoted to one of the aforesaid levers, a support for the lower ends of the harness jacks extending between said side plates, means on said jacks and said support defining mutually engaging arcuate bearing surfaces having their center located within said zone of operation of the levers and hooks, and bolts having their axes located along said center to secure the support to the side plates of the dobby, whereby said support is capable of assuming a plurality of positions with respect to said side plates around said bolts while at the same time maintaining the arcuate bearing surfaces of said support concentric with said center.

3. In a loom dobby having spaced side plates between which are located a plurality of levers each of which is provided with a pair of hooks to be actuated by reciprocating knives mounted on and sliding relatively to the side plates, the dobby having a top cross girt to engage the upper part of each lever and having also a harness lifter jack pivoted to each lever, the upper parts of the jacks being acted upon by a constantly exerted force to move in a direction away from said cross girt and the latter being between the levers and the jacks, a bottom cross girt located between the lower ends of the levers and the jacks placed for engagement with the lower parts of the levers, the jacks tending to hold said levers against the top and bottom girts, the bottom girt being formed with an arcuate surface, and the lower end of each jack being provided with an arcuate bearing to have sliding contact with the arcuate surface on the bottom girt.

4. In a loom harness controlling mechanism having a harness jack movable through a given range of angular motion, a fixed bearing having an arcuate bearing surface, a slide bearing formed on the lower end of the jack and having an arcuate surface to slide over said fixed bearing when the jack moves through said range of angular motion, a guide on said jack having a guiding surface formed as an arc substantially concentric with said slide bearing, and a retaining means lying close to said guide and spaced above the bottom of said guiding surface when the jack is at one extreme of said range of an-

gular motion and located close to the bottom of said guiding surface when said jack is in the other extreme of its range of angular motion.

5. In a loom dobby having a dobby back lever and hooks connected thereto to engage reciprocating knives to move a harness jack connected to the lever through a given range of angular motion, a bearing fixed to the dobby and having an arcuate bearing surface, a foot formed on the lower end of the jack and having an arcuate sliding bearing surface on one side thereof for engagement with said fixed bearing and having the other side thereof substantially concentric with the slide bearing, said foot to slide over the fixed bearing through the aforesaid range of angular motion, and a retainer adjacent to said other side of the foot and located a substantial distance above the bottom of said foot when the jack is in one extreme of said range of angular motion and located near the bottom of said foot when the jack is in the other extreme of said range of angular motion.

6. A combined dobby cross girt and harness jack bearing for a dobby having spaced side plates and operating with a dobby back lever pivoted to a harness jack which has an arcuate bearing surface, said combined cross girt and jack bearing having a surface on one side thereof for engagement with the lever and an arcuate surface on the other side thereof for sliding engagement with the bearing of the jacks, and ears formed on the ends of the cross girt provided with holes to receive attaching means supported by the side plates, said holes having their axes concentric with the arcuate surface on said other side of the combined cross girt and jack bearing.

7. A harness jack for a dobby having a jack support formed with an arcuate bearing surface and a supporting pin spaced from said arcuate bearing surface, said jack having a foot at the lower end thereof located between two substantially concentric surfaces one of which is formed for sliding engagement with the arcuate surface of the jack support and the other of which is located for engagement with said pin, said foot throughout its length having a width not substantially greater than the distance between said pin and said arcuate surface on the jack support.

CLARENCE R. KRONOFF.
